(57) **CLAIM**

The ornamental design for a perforated cell encapsulation device, as shown and described.

DESCRIPTION

FIG. 1 is a perspective view of the first embodiment of a cell encapsulation device showing our new design;

FIG. 2 is a top plan view thereof;

FIG. 3 is a bottom plan view thereof; and,

FIG. 4 is a back elevational view thereof;

FIG. 5 is a front elevational view thereof;

FIG. 6 is a left side elevational view thereof;

FIG. 7 is a right side elevational view thereof;

FIG. 8 is a perspective view of the second embodiment of a cell encapsulation device showing our new design;

FIG. 9 is a top plan view thereof;

FIG. 10 is a bottom plan view thereof; and,

FIG. 11 is a back elevational view thereof;

FIG. 12 is a front elevational view thereof;

FIG. 13 is a left side elevational view thereof;

FIG. 14 is a right side elevational view thereof;

FIG. 15 is a perspective view of the third embodiment of a cell encapsulation device showing our new design;

FIG. 16 is a top plan view thereof;

FIG. 17 is a bottom plan view thereof; and,

FIG. 18 is a back elevational view thereof;

FIG. 19 is a front elevational view thereof;

FIG. 20 is a left side elevational view thereof; and,

FIG. 21 is a right side elevational view thereof.
